No. 728,080.

PATENTED MAY 12, 1903.

G. T. BROWN.
LAMP BURNER AND FONT.
APPLICATION FILED JULY 8, 1902.

NO MODEL.

UNITED STATES PATENT OFFICE.

GEORGE T. BROWN, OF BALTIMORE, MARYLAND, ASSIGNOR OF ONE-HALF
TO JAMES D. BROWN, OF BALTIMORE, MARYLAND.

LAMP BURNER AND FONT.

SPECIFICATION forming part of Letters Patent No. 728,080, dated May 12, 1903.

Application filed July 8, 1902. Serial No. 114,798. (No model.)

To all whom it may concern:

Be it known that I, GEORGE T. BROWN, of Baltimore, in the State of Maryland, have invented certain new and useful Improvements in Lamp Burners and Fonts; and I hereby declare that the following is a full, clear, and exact description thereof, reference being had to the accompanying drawings, which form part of this specification.

- 10 This invention is an improvement in burners and fonts for lamps, lanterns, &c.; and its objects are, first, to produce a burner of very simple construction, the parts of which can be readily assembled and securely connected without solder; second, to make a slip-joint connection between burner and font collar or nipple and to utilize the wick-raiser rod as a means for preventing rotation of burner on font; third, to utilize the wick-raiser rod as a means for supporting and holding the wick-tube in position in the burner; fourth, to utilize the air-chamber ring of the burner as a means for securing the wick-tube support or nipple securely to the font and to 25 also utilize this ring as the chimney or globe support or connection, and, finally, to construct the burner so that the wick-tube will hold securely in its proper position within the burner without using a bottom plate to hold 30 it in position, as is usual, and thus providing a recessed burner open at the bottom, enabling it to be slipped on or fastened to the outside of the font-collar.

With these ends in view the invention consists in the novel constructions and combinations of parts summarized in the claims following the detailed description of the invention, as illustrated in the accompanying drawings, in which—

- 40 Figure 1 is a sectional elevation through the complete burner, the latter being provided with chimney-engaging fingers. Fig. 2 is a side view thereof. Fig. 3 is a horizontal section through Fig. 1. Fig. 4 is a detail view of 45 a slight modification of wick-tube. Fig. 5 is a detail sectional view of the font collar or nipple. Fig. 6 is a detail enlarged vertical section of a slight modification. Figs. 7 and 8 are detail side and sectional views of a 50 modification of burner. Figs. 9 and 10 are detail side and sectional views of another pre-

ferred form in certain cases. Fig. 11 is a detail sectional view showing an air-cap on the burner.

The font 1 may be of any suitable construction and provided with a collar 2 for the attachment of the nipple of the burner. In the preferred construction this collar instead of being threaded, as it usually is, is plain finished, and the burner-nipple 3 is adapted to be slipped or telescoped therewith instead of being screwed thereto, it being preferably formed to slip over the collar. The collar, moreover, is provided with opposite vertical slots 2^a for the accommodation of the wick-raiser rod 5, which slots and rod not only prevent the burner casually turning on the plain collar, but also insure the proper registration of the wick-tube with the combustion plate or hood of the burner.

The burner-nipple 3 is preferably drawn from one piece of metal and is shaped to properly engage with and fit the collar, preferably slipping over the latter, as indicated in Figs. 1 and 3. Extending centrally through the top of the nipple is a wick-tube 4, which may be drawn or bent into proper shape to receive and guide the wick. The top of the nipple is suitably apertured for the passage of the wick-tube, and the tube should not have any lateral play in the aperture. Said tube is upheld in position and in the nipple by the wick-raiser rod 5, which passes through the nipple, transfixing the opposite walls thereof, and lies close against the wick-tube and is connected therewith, as and for the purposes hereinafter specified.

In Figs. 1 and 3 the wick-raiser rod 5 has but one star-wheel 5^a, which engages the wick through an opening 4^b in the wick-tube. In Fig. 4 two star-wheels 5^a are shown on the rod, and the tube is correspondingly apertured. The wick-raiser rod may be connected to the wick-tube by passing it through eyes 4^a, struck up from the metal of the wick-tube, as indicated in Figs. 1, 3, and 6. In Fig. 4 a single eye 4^b is shown between the star-wheels, through which eye the wick-raiser rod passes. Instead of striking up eyes 4^a or 4^b from the wick-tube ears 4^d may be struck up therefrom at opposite sides of the star-wheel opening, as in Figs. 7 and 8, said ears being transfixed

by the rod 5 and performing the same office as eyes 4^a. Figs. 9 and 10 show a very useful and preferable construction if the tube is not of sufficient thickness or ductility to permit eyes to be struck up therefrom, a U-shaped yoke 4^c being placed against the wick-tube with its ends projecting in front thereof and forming eyes which are transfixed by rod 5, so as to hold the wick-tube in place. In this construction the wick-tube may be beaded above the nipple and below the yoke, as at 4^f 4^g, to prevent vertical displacement of the tube. In all these constructions, however, the wick-tube is firmly held and centered in position within the nipple by the slot in top of nipple, the wick-wheel, and the wick-raiser rod 5, which latter serves the double purpose of raising the wick and locking the wick-tube in position within the nipple, enabling soldering to be dispensed with. These several modifications show how the wick-tube can be fastened and supported in place within the nipple by the wick-raiser rod in various ways, so that soldering may be dispensed with, and I do not wish to limit myself to any particular connection between wick-tube and wick-raiser rod to accomplish this purpose.

In Fig. 6 I have indicated how the nipple might be threaded to screw onto a collar; but this threaded connection is quite old and is not claimed herein.

In Fig. 11 I have shown a burner similar to that shown in Figs. 9 and 10, with an air-cap 8 attached to its top for the purpose of conducting air to the top of wick-tube and producing a better flame. Such air-caps are old and are not specifically claimed herein. They perform the same office as cap 6^b in Fig. 1—to wit, increase the brilliancy of the flame—and they may be readily attached to any of the burners shown.

When the nipple is slipped onto the collar, the projecting ends of rod 5 engage slots 2^a and prevent the burner turning. When applied to lamps, the slots 2^a may have horizontal extensions 2^b at bottom, as indicated in Fig. 5, so that after the nipple is slipped on the collar it can be slightly turned thereon, so as to engage rod 5 with the portions 2^b of the slots and lock the nipple on the collar; but when used with chimney or globe burners I prefer to make the slots 2^a straight and vertical, so that the wick-raiser rod when engaged therewith will keep the burner in proper position and prevent rotation thereof. In such cases suitable means should be provided for holding the nipple down on the collar, and this may be readily accomplished by utilizing the combustion or air chamber of the burner, as indicated in the drawings. In Fig. 1 the font has an annular shoulder 1^a exterior to and larger than the collar and adapted to be engaged by an annular perforated ring 6, forming the outer wall of the air-chamber of the burner. This shoulder 1^a I consider a very useful and novel feature, as it affords a simple and efficient means for

centering and retaining the burner on the font in connection with the ring 6 and devices hereinafter described. On this ring is supported the perforated cap 6^a and flame-guard 6^b, of usual or other suitable construction, and this ring may also be provided at top with any suitable engaging or retaining devices to connect a globe or chimney with the burner, as desired. The burner is shown as provided with chimney-engaging fingers 6^c; but the particular kind of engaging devices is immaterial and can be varied to suit the use or purpose of the lamp or lantern for which the burner is designed.

The ring 6 may be locked to the font in any desired way, a simple and efficient means being shown in the drawings, such means comprising pins or lugs 7^a, projecting horizontally from the top of shoulder 1^a and which may be conveniently formed by wires 7, placed on top of the font and suitably secured in place, as by passing them through eyes 1^b, struck up from the metal of the top of font, as shown in Figs. 3 and 5, these wires being preferably arranged parallel with and on opposite sides of rod 5, as indicated in Fig. 3. The ring 6 is provided with inverted L-shaped slots 6^d in its lower edge adapted to engage with lugs 7 when the ring is slipped onto the shoulder, and then by partially turning the ring it is locked to the font by lugs 7, entering the horizontal portions of slots 6^d, as shown. The ring is also provided in its lower edge with slots 6^e to accommodate the projecting end or ends of rod 5, as shown in the drawings. When the ring is in place, the slots 6^e prevent the wick-raiser rod 5 rising, and consequently the ring when in position and locked will hold the burner-nipple and wick-tube firmly down upon the font-collar and maintain tight joints therebetween.

In some cases the chimney or globe supports might be directly connected to the nipple, as indicated at 9 in Fig. 7, and when the wick-rod 5 is locked to the collar by engaging the slots 2^b, as described, the burner and chimney will be securely held to the font in a very simple manner.

I do not wish to restrict myself to the employment of the ring 6 nor the particular fastening means shown and refer to the appended claims for concise summaries of what I deem the essential features and combinations of parts for which I desire protection.

Having thus described my invention, what I therefore claim as new, and desire to secure by Letters Patent thereon, is—

1. In a burner, a nipple, a wick-tube, and a wick-raiser rod securing the tube to the nipple, substantially as described.
2. A burner comprising a bottomless nipple, a wick-tube passing through an aperture in the top of the nipple, and a wick-raiser rod transfixing the nipple and securing the tube therein, substantially as described.
3. In a burner, a nipple, a wick-tube, and a wick-raiser rod secured to the nipple at

- right angles to the tube, and whereby the latter is fastened to the former, substantially as described.
4. In combination, a plain font-collar, a nipple adapted to fit the collar, a wick-tube, and a wick-raiser rod securing the tube in position in the nipple, substantially as described.
5. A burner comprising a bottomless nipple having an aperture in its top for the passage of a wick-tube, the wick-tube, a wick-raiser rod transfixing the nipple and means for fastening the rod to the tube, substantially as described.
- 15 6. A burner comprising a nipple, a wick-tube therein, eyes on the tube within the nipple, and a wick-raiser rod transfixing the nipple and eyes, for the purpose and substantially as described.
- 20 7. In a burner, a nipple, a wick-tube transfixing the same, a wick-raiser rod transfixing the nipple at right angles to the tube, and connections between the rod and tube whereby the latter is fastened within the nipple, substantially as described.
- 25 8. In a burner, a nipple, a wick-tube therein provided with eyes, and a wick-raiser rod at right angles to the tube and engaging the eyes and thereby fastening the tube in the nipple, substantially as described.
- 30 9. In a burner, a nipple, a wick-tube therein, and a wick-raiser rod transfixing the nipples at right angles to the tube and engaging eyes on the latter, and fastening the tube to the nipple, substantially as set forth.
- 35 10. In combination, a vertically-slotted collar, and a burner engaging the same having a transverse wick-raiser rod engaging the slots in the collar, substantially as described.
- 40 11. In combination, a vertically-slotted collar, a nipple engaging the same, a wick-tube in the nipple, and a transverse wick-raiser rod in the nipple engaging the slots in the collar, substantially as described.
- 45 12. In combination, a font-collar having slots, and a burner comprising a nipple removably fitted to the collar, a wick-tube, and a wick-raiser rod at right angles to the tube engaging the slots in the collar, substantially as described.
- 50 13. In combination, the font-collar having slots; and a burner, comprising a nipple removably fitted to the collar, a wick-tube in the nipple, and a wick-raiser rod transfixing the nipple at right angles to the tube and securing the latter in position in the nipple and also engaging the slots in the collar, substantially as described.
- 55 14. In combination, a font, a nipple fitted thereto, a wick-tube, and a wick-raiser rod attached to the nipple; with a ring having slots for the accommodation of the wick-raiser rod, and means for fastening the ring to the font, substantially as described.
15. In combination, a font, a nipple fitted thereto, a wick-tube in the nipple, and a wick-raiser rod at right angles to the tube, securing the latter in the nipple; with a ring, and means for fastening the ring to the font to hold the nipple on the collar, substantially as described.
16. A lamp-font having a collar, and an annular shoulder exterior to the collar, a burner fitted to the collar, and a ring fitted to the shoulder provided with slots for the accommodation of the wick-raiser rod, and means for securing the ring to the font.
17. In combination, a lamp-font having a collar, and an annular shoulder exterior to the collar, a burner removably fitted to the collar, and having a wick-raiser rod projecting beyond the shoulder, a ring fitted to the shoulder and provided with slots for the accommodation of the wick-rod, and means for locking the ring to the shoulder thereby holding the burner in position, substantially as described.
18. In combination, a font, a slotted collar thereon, a nipple removably fitted to the collar, a wick-tube in the nipple, and a wick-raiser rod secured to the nipple and fastening the tube therein; with a removable ring exterior to the collar, and means for fastening the ring to the font, comprising pins and slots, said ring having slots to accommodate the wick-raiser rod, substantially as described.
19. In combination, a font, a slotted collar thereon, a nipple removably fitted to the collar, a wick-tube in the nipple, and a wick-raiser rod transfixing the nipple and fastening the tube therein, and also engaging the slots in the collar when the nipple is slipped thereon; with a removable ring exterior to the collar, and means for fastening the ring to the font, said ring having slots to accommodate the wick-raiser rod, substantially as described.
20. The combination of the font having a slotted collar, and an annular shoulder exterior to the collar; with a nipple slipped onto the collar, a wick-tube, a wick-raiser rod transfixing the nipple horizontally and connected with the wick-tube, and engaging the slots in the collar, a ring fitted to the shoulder provided with slots for the accommodation of the wick-raiser rod, means for fastening the ring to the font, and globe or chimney engaging devices above the ring, substantially as set forth.
- In testimony that I claim the foregoing as my own I affix my signature in presence of two witnesses.
- GEORGE T. BROWN.
- In presence of—
ARTHUR E. DOWELL,
JAMES R. MANSFIELD.
